No. 794,668.

PATENTED JULY 11, 1905.

P. H. & F. F. DOWNES.

FLAGSTAFF.

APPLICATION FILED JUNE 10, 1904.

UNITED STATES PATENT OFFICE.

PHILIP H. DOWNES AND FRANK F. DOWNES, OF BOSTON, MASSACHUSETTS.

FLAGSTAFF.

SPECIFICATION forming part of Letters Patent No. 794,668, dated July 11, 1905.

Application filed June 10, 1904. Serial No. 212,034.

To all whom it may concern:

Be it known that we, PHILIP H. DOWNES and FRANK F. DOWNES, citizens of the United States, and residents of Boston, in the county 5 of Suffolk and State of Massachusetts, have invented new and useful Improvements in Flagstaffs, of which the following is a specification.

Our invention relates to flag-supports and 10 the like; and its object is to provide an improved article of this class.

An objection to flag supports, staffs, and the like as heretofore constructed has been that changes in the direction of the wind 15 would in a comparatively short while after the flag was raised wind or twist the flag about the staff, so that it could not be read. Also it has heretofore been customary, particularly on board yachts and other vessels, to raise and 20 lower signal-flags and the like by means of two lines, one passing from the deck through a sheave or block near the top of the mast or other spar of the vessel and thence to the middle of the flagstaff, where its end was fastened, and the other line being fastened to the 25 handle end of the flagstaff and passing directly to the deck. The first line was used to raise the flag to the top of the mast and to hold it in position with the assistance of the 30 second line, the lower end of both lines being made fast to a cleat on the mast or other fixture near the deck to secure the flag in its raised position. The second line, besides assisting in holding the flag in its raised position, 35 was also used in hauling down the flag. The objection to such devices was that while the first line which passed through the block or sheave would hold the middle portion of the staff snugly against the mast the other line 40 running free from the end of the staff to the deck would stretch and give and not hold the handle end of the staff in place. As a result the staff would not only be swung about by the wind, so that the signal or flag was poorly 45 displayed and the lines chafed, but it was impossible as a practical matter to fasten the flag in a raised position otherwise than with its staff more or less canted or inclined from a vertical position, and therefore the flag would

be stretched unevenly by the wind and poorly 50 displayed.

In our improved flag-support the staff of the flag comprises a butt or body portion and a flag-carrier rotatably mounted on said body portion near one end thereof. The advantages of this construction are that the flag being fastened to the rotatable carrier, which is free to turn on the body portion, said flag cannot become twisted or wound about the staff by the wind, as has heretofore been the case, 60 and this is an especially-valuable feature when applied to signal pennants or flags, which it is important should fly clear and open in order that they may be read.

In its best form our improved flag-support 65 comprises also a mast or spar, on which are journaled two blocks or sheaves located at separated points—one preferably near the outer or upper end thereof and the other at a point nearer the middle of the mast. Two lines are 70 provided—one for each sheave—and of these the line of the inner or lower sheave is fastened to the flagstaff near the handle end, while the other line is fastened to the flagstaff at a point nearer the middle thereof. By this 75 construction when the flag is raised its staff is held rigidly to the mast at two separated and determinate points, so that it is not canted with relation to the mast or spar and cannot be swung about by the wind or by the pitching 80 of the vessel.

In the accompanying drawings, Figure 1 is a central longitudinal sectional view of a portion of the flagstaff hereinafter described. Fig. 2 is an elevation of our improved flag- 85 support. Fig. 3 is a plan view of the upper end of the mast or spar hereinafter described.

Having reference to the drawings, B represents a flagstaff, of which the main body portion or butt b is preferably of wood. The 90 body portion b is provided at one end thereof with a conical bearing ring or block b', fixed rigidly in place by a screw b², driven into the end of said body portion, said bearing-ring b' being interiorly threaded and screwed onto 95 the screw b² against a flange b³ before said screw is driven into place in the end of body b. Upon the outer end of screw b² is mounted

the interiorly-threaded lower end of a hollow stem or tube b^4 , whose upper end is also interiorly threaded and has mounted therein a second screw b^5 . Upon the outer end of screw b^5 is mounted an interiorly-threaded conical bearing block or ring b^6 , opposed to the ring b^7 and locked in position on said screw b^5 by a check-nut b^7 and clamping-screw b^8 , carried by the latter. It will thus be seen that screws b^2 and b^5 , together with the tube b^4 , constitute an extension of the main body portion b , which is smaller in diameter than said body portion. Surrounding this extension is a flag-carrier, (shown in Figs. 1, 2, and 3 as a sleeve b^9), within the lower end of which is fixed a cup-bearing b^{10} , opposed to the conical ring b^6 , and within the upper end of sleeve b^9 is fixed a cup-bearing b^{11} , opposed to the conical ring b^6 . Between ring b^6 and cup b^{10} are arranged antifriction-balls b^{12} , and between ring b^6 and cup b^{11} are arranged antifriction-balls b^{13} .

The upper end of sleeve b^9 terminates in a ferrule b^{14} , brazed or otherwise fastened partly within the end of said sleeve, and upon the projecting end of this ferrule b^{14} is forced a cap b^{14} , covering the end of the extension and frictionally held in place, so that when the bearings on which sleeve b^9 turns wear said cap can be removed for the purpose of adjusting ring b^8 to take up such wear. Cap b^{14} being upon the outside of ferrule b^{14} , a weather-tight joint is provided at that point. Upon the body portion b , adjacent sleeve b^9 , is fixed a ferrule b^{15} , reduced in diameter at its outer end so as to fit within the lower end of sleeve b^9 and provide a weather-tight joint at this point also.

Upon its exterior sleeve b^9 is made with two eyes b^{16} , to which a flag can be fastened, as shown in Fig. 1.

By having the sleeve b^9 rotatably mounted on the body portion b and the flag attached to the sleeve the flag C cannot wrap about the staff, which has been an objectionable characteristic of flagstaffs as heretofore constructed.

The reason for making the extension of the body portion of the staff in three parts b^2 , b^4 , and b^5 is because with different-sized flags sleeves b^9 of different lengths are required, and in the manufacture of the staffs they may be adapted to different-sized flags by using sleeves b^9 and tubes b^4 of the proper length without other changes in the parts.

In Fig. 2, A represents a mast or spar provided at its upper or outer end with a head a , made with a socket a' . Immediately below head a mast A is made with a transverse opening a^2 , in which is journaled a sheave a^3 , and at a point nearer the other end of the mast or spar A the latter is made with a like transverse opening a^4 , in which is journaled a second sheave a^5 . Fast to the handle end of flagstaff B is a line a^6 , extending from said

staff over sheave a^5 to the base of the mast A, 65 and fastened to staff B at a point nearer its other end is another line a^7 , extending from said staff over sheave a^3 to the base of mast A. By means of these two lines a^6 and a^7 staff B can be raised into a vertical position at the 70 top of the mast A, with the staff occupying the socket a' . By making the lower ends of lines a^6 and a^7 fast to a cleat a^8 near the lower end of mast A staff B may be secured in that position. Preferably the line a^6 is endless— 75 that is, its lower end extends from the base of mast A upwardly in a third line a^9 , fastened at its upper end to the end of staff B. This line a^9 is provided mainly for use in lowering staff B. By this construction the staff B is 80 held firmly and securely against A at two separated and determinate points, so that it cannot be swung about by the wind or by the pitching of a vessel in the manner that has heretofore characterized devices of this kind, 85 and as a result the flag is better displayed than has heretofore been the case, which is important when the flag is a signal-pennant.

While the flagstaff above described, with its swiveled carrier b^9 , serves very well by 90 itself to prevent the flag twisting or wrapping about said staff even when held in a canted position, yet, as will be obvious, the best results in this direction will be secured when the novel hoisting means just described is 95 combined therewith and by which the staff is held in a perpendicular position.

What we claim is—

1. A flagstaff comprising a butt; an extension at the outer end of the butt; a rotatable flag-holding sleeve surrounding said extension, and means near the outer end of the extension for holding the sleeve in place, the extension being made up of two screws and a stem one of the screws connecting one end of the stem with the butt and the other screw being fast to the outer end of the stem and carrying the means for holding the sleeve in place. 105

2. A flagstaff comprising a butt; an extension at the outer end of the butt; a rotatable flag-holding sleeve surrounding said extension, means near the outer end of the extension for holding the sleeve in place, and a cap fixed to and closing the outer end of the sleeve, the extension being made up of two screws and a stem, one of the screws connecting one end of the stem with the butt and the other screw being fast to the outer end of the stem and carrying the means for holding the sleeve in place. 115

3. A flagstaff comprising a butt; an extension at the outer end of the butt made up of two screws and a stem one of the screws connecting one end of the stem with the butt and the other screw being fast to the outer end of the stem; a rotatable flag-holding sleeve surrounding said extension made at each end 125

with an interior annular bearing; an annular bearing-ring surrounding the extension near its inner end and opposed to the annular bearing within the adjacent end of the sleeve, and 5 an annular bearing-ring mounted upon the screw at the outer end of the extension and opposed to the annular bearing within the adjacent end of the sleeve.

4. A flagstaff comprising a butt; an extension at the outer end of the butt made up of two screws and a hollow stem or tube, one of the screws connecting one end of the hollow stem with the butt and the other screw being fast to the outer end of the stem; a rotatable 10 flag-holding sleeve surrounding said extension and made at each end with an interior

annular bearing; an annular bearing-ring surrounding the extension near its inner end and opposed to the annular bearing within the adjacent end of the sleeve; an annular bearing- 20 ring mounted upon the screw at the outer end of the extension and opposed to the annular bearing within the adjacent end of the sleeve, and a cap fast to and closing the outer end of the sleeve. 25

Signed by us at Boston, Massachusetts, this 2d day of May, 1904.
